BURSTER OR SIMILAR ARTICLE

Andrew L. Alger, Wilmette, and Kim Yamasaki, Lombard, Ill., assignors to Varco Incorporated, Barrington, Ill.

Filed Sept. 16, 1974, Ser. No. 506,186

Term of patent 14 years

Int. Cl. D18—04

U.S. Cl. D55—1 A

FIG. 1 is a perspective view of two adjacent sides, including the front side, of a burster or similar article showing our new design;

FIG. 2 is a rear elevational view;

FIG. 3 is a side elevational view from the right of FIG. 2;

FIG. 4 is a side elevational view from the left of FIG. 2; and

FIG. 5 is a top plan view.

The bottom side is plain and unornamented while the front and rear sides differ only in the presence of a label area near the upper left hand corner of the front side.

We claim:

The ornamental design for a burster or similar article, substantially as shown and described.
